Primary Examiner — Catherine R Oliver-Garcia*(74) Attorney, Agent, or Firm* — Hooker & Habib, P.C.(57) **CLAIM**

The ornamental design for a bandoleer, as shown and described.

DESCRIPTION

FIG. 1 is a front-top perspective view of the bandoleer; FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front-top perspective view of a second embodiment bandoleer;

FIG. 9 is a front view thereof;

FIG. 10 is a rear view thereof;

FIG. 11 is a left side view thereof;

FIG. 12 is a right side view thereof;

FIG. 13 is a top plan view thereof; and,

FIG. 14 is a bottom plan view thereof.

The broken line portions of the figure drawings are included to show unclaimed subject matter and form no part of the claimed design.

1 Claim, 6 Drawing Sheets(56)
